AXIAL COMPRESSOR

Francis Henry Keast, Toronto, Ontario, Canada, assignor to A. V. Roe Canada Limited, Malton, Ontario, Canada, a corporation

Application December 2, 1950, Serial No. 198,779

4 Claims. (Cl. 230—122)

This invention relates to axial air compressors, and particularly to those used in aircraft gas turbine engines.

The main object of the invention is to provide in a compressor an annular air passage which is so arranged as to distribute effectively the loading on the various blades, taking into consideration the high Mach numbers encountered in the first stage.

Another object of the invention is to eliminate as far as possible the manufacturing difficulties involved in making fundamentally different blades for each stage of a compressor.

Other objects and advantages of the invention will be apparent during the course of the following description.

In the accompanying drawings forming a part of this specification, and in which like reference characters designate like parts throughout the several views:

Fig. 1 is a longitudinal cross-sectional view of the upper half of a compressor, the lower half which is not shown being a mirror image of the said upper half; and

Fig. 2 is a set of diagrammatic representations of the air velocities at various stages in the compressor.

For convenience, the axial compressor depicted in Fig. 1 is shown as having ten stages, but the claimed invention is not confined to compressors of any particular number of stages, and its principles may be applied to any axial compressor of the kind described. Each stage comprises one circumferential row of rotor blades mounted on the rotor and one circumferential row of stator blades mounted on the stator casing. In Fig. 1 the rotor blades of the first stage are designated 1R, while the symbol 1S designates the corresponding stator blades. This form of identification is used throughout the various stages, in the last of which the symbols 10R and 10S indicate the tenth or last stage of rotor and stator blades respectively. Immediately forward of the first row of rotor blades 1R is a circumferential row of inlet guide vanes 11, and at the other end of the compressor the stator blades 10S discharge the compressed air into diffusers 12. All the rotor blades are mounted externally on the rotor drum 13 while the stator blades are mounted internally on the casing 14. It will be understood by those familiar with axial compressors of this type, that the front bearing of the rotor 13 is mounted in a housing 15 which is supported from the casing 14 by long-chord streamlined struts 16, so that the inlet guide vanes 11 may be supported at their outer diameter on the casing 14 and at their inner diameter on the housing 15.

The velocities at which the air enters and leaves certain stages of the compressor, at some specific radius, are illustrated diagrammatically in Fig. 2 by means of vectors, each vector representing the corresponding air velocity in magnitude, direction and sense. The air emerges from the inlet guide vanes 11 with a velocity which is represented by the vector V_1 and this vector may be resolved into axial and tangential components, namely the vectors V_{a1} and V_{w1} respectively. Now if u is the tangential velocity of the rotor blades 1R at the radius under consideration, it is evident that the vector

2

V_{r1} , representing the relative velocity at which the air is introduced to the said rotor blades, is made up of two components V_1 and u , the u vector being of equal magnitude and opposite sense to the tangential velocity of the blades.

The velocity relative to the rotor blades 1R at which the air leaves these blades is depicted by the vector V_{r2} and it follows that the absolute velocity of this air is represented by the vector V_2 made up of the components 10 V_{r2} and a vector of magnitude u , representing the tangential velocity of the blades. This absolute velocity V_2 is the velocity at which the air is introduced to the first row of stator blades 1S and it may be resolved axially and tangentially into the components represented by the vectors V_{a2} and V_{w2} respectively.

The air leaving the first row of stator blades 1S has a velocity represented by the vector V_3 , having a tangential component V_{w3} , and this air is introduced to the second row of rotor blades 2R with a velocity, relative to the said rotor blades, represented by the vector V_{r3} . The velocity V_{r3} is the resultant of the component V_3 and, as in the case of V_{r1} (since all the rotor blades are mounted on a common rotor 13), a component u of equal magnitude and opposite sense to the tangential velocity of the rotor blades.

By similar reasoning, the vector diagram for each stage of the compressor may be developed: it is believed that from the foregoing description the series of suffixes will be sufficiently understood and therefore the diagrams for the intermediate stages are not shown in the drawing.

Those familiar with the compressor art will understand that the work done by the rotor blades 1R on a unit mass (1 lb.) of air is

$$\frac{u}{g} (V_{w2} - V_{w1})$$

where g is the acceleration due to gravity. As a result of this work the air experiences a temperature rise and therefore the speed of sound in that air is higher as the air leaves the first row of stator blades 1S than it was when the air left the inlet guide vanes 11. Since the velocity at which the air may be introduced to any row of rotor or stator blades is limited by the critical Mach number, it will be evident that due to the aforesaid increase in the speed of sound it is permissible to introduce the air to the second row of rotor blades at a velocity greater than the velocity at which it was introduced to the first row; in other words V_{r3} may be greater than V_{r1} . By reference to the vector diagrams it will be seen that the magnitude of the relative velocity at which the air is introduced to a row of rotor blades is dependent upon the difference between the tangential velocity of the said blades and the whirl velocity, that is the tangential component of the velocity at which the air leaves the preceding stator blades or guide vanes; e. g. for a given value 40 of u , the magnitude of V_{r1} will be reduced by an increase in the value of V_{w1} . Hence, since as has been shown 45 V_{r3} may be greater than V_{r1} , and since u is constant at the air to the second row of rotor blades at a velocity greater than the velocity at which it was introduced to the first row; in other words V_{r3} may be greater than V_{r1} . By reference to the vector diagrams it will be seen that the magnitude of the relative velocity at which the air is introduced to a row of rotor blades is dependent upon the difference between the tangential velocity of the said blades and the whirl velocity, that is the tangential component of the velocity at which the air leaves the preceding stator blades or guide vanes; e. g. for a given value 50 of u , the magnitude of V_{r1} will be reduced by an increase in the value of V_{w1} . Hence, since as has been shown 55 V_{r3} may be greater than V_{r1} , and since u is constant at the a given radius, V_{w3} may be less than V_{w1} .

From similar considerations of the Mach number permissible on the stator blades, it may be deduced that V_4 may be greater than V_2 and the tangential component V_{w4} may be greater than V_{w2} . Thus the work done by the second row of rotor blades 2R, i. e.

$$\frac{u}{g} (V_{w4} - V_{w2})$$

may be appreciably greater than the work done by the first row of rotor blades 1R, i. e.

$$\frac{u}{g} (V_{w2} - V_{w1})$$

as stated hereinbefore.

In order to facilitate production it is desirable that identical blade forms should be employed at each stage, from which it follows that each stage will do the same amount of work. However from the foregoing paragraphs it will be understood that the first stage should be treated as an exception and that the subsequent stages only should be arranged so that each will do work equal to

$$\frac{u}{g} (Vw_4 - Vw_3)$$

It will be explained later that the last stage must also be treated as an exception; thus only the intermediate stages, namely the second to the ninth in the compressor described, may embody blading which, at any given radius, is identical in aerofoil section and incidence to the rotor blades 2R and the stator blades 2S of the second stage.

Since the axial velocity Va of the air stream is substantially constant, from considerations of mass flow it will be understood that the cross-sectional area of the annular air passage between the rotor drum and the stator casing is inversely proportional to the density of the air. At any stage the ratio of the density at outlet to the density at inlet is proportional to a positive power (+) of the ratio of the temperature at outlet to the temperature at inlet, the compression being adiabatic. Since an equal amount of work is done by each stage from the second to the ninth inclusive, the temperature rises by the same amount across each stage, and it follows that the ratio of the temperature at outlet to the temperature at inlet of each stage decreases progressively along the passage; therefore the ratio of the cross-sectional area of the inlet to the cross-sectional area of the outlet of each also decreases progressively. In consequence the annular air passage converges progressively from the second to the ninth stage. In the compressor described, the radius of the rotor drum is constant from the second to the sixth stage so that identical rotor blades may be used by cropping the tips to suit the convergence of the annular passage. The corresponding stator blades are similarly identical to one another but in this case it is necessary to crop the roots rather than the tips, a procedure which may present some difficulties depending upon the type of blade construction employed, though still obviously advantageous, from the manufacturing viewpoint, over the use of blades of different aerofoil section at each stage.

Towards the rear of the compressor it is desirable to increase the mean radius of the annular air passage so that the diffusers 12 may lead smoothly from the compressor into the combustion chambers 17, which, by reason of their size, must necessarily be situated on a fairly large pitch circle about the axis of the engine. Therefore from the seventh to the ninth stages in this construction, the outer radius of the annulus, that is the inner radius of the stator casing, is held constant and the radius of the rotor drum is progressively increased. This feature is apparent in Fig. 1, from the change in the longitudinal contour of the rotor drum immediately forward of the blades 7R.

It will be understood that from the seventh to the ninth stages the blades used may be of the same aerofoil section and incidence as those used from the second to the sixth stages, but from the seventh to the ninth stages the tips of the stator blades and the roots of the rotor blades must be cropped to conform to the convergence of the annular passage.

Reverting to the first stage, as has been indicated the rapidity of convergence of the annular air passage across any particular stage is determined by the ratio of the temperature at outlet to the temperature at inlet, that is by the amount of work done by the stage, and since the work done by the first stage, i.e.

$$\frac{u}{g} (Vw_2 - Vw_1)$$

is less than the work done by succeeding stages the passage must converge less rapidly over the first stage than over the subsequent stages. Furthermore, considering the first row of stator blades 1S, if Vw_3 is less than Vw_1 , the said stator blades must remove all the whirl or tangential velocity contributed by the first row of rotor blades 1R together with some of the whirl originally contributed by the inlet guide vanes 11. Thus the pressure rise across the stator blades 1S is very high, that is the blades are heavily loaded. Now, as will be known to those skilled in the art, across any row of stator blades, neglecting the losses which are small,

$$p + \frac{1}{2} \rho [V_a^2 + V_w^2] [1 + f(M)] = \text{constant}$$

where p is the pressure, ρ is the density, V_a is the axial velocity, V_w is the whirl velocity, and $f(M)$ is a correction for Mach number M . Across the first row of stator blades, V_w is reduced by a large amount, so that p rises by a large amount, and to keep this inevitable pressure rise to a minimum, the shape of the annular passage must be so arranged that V_a is increased, or at least not reduced, in passing through this particular row of stator blades. This result may be achieved by lengthening the trailing edges of the rotor blades 1R and the leading edges of the stator blades 1S.

These two characteristics, namely the less rapid convergence of the annular passage over the first stage and the lengthening of the leading edges of the stator blades, are shown in Fig. 1 by a change in the longitudinal contour of the stator casing at the point 18 and by another change in the longitudinal contour of the rotor at the point 19. It will be appreciated that the cross-sectional area of the annular passage diminishes more rapidly across the row of stator blades 1S of the first stage than across the stages intermediate the first stage and the last stage.

The design of the last stage, namely the tenth stage in the compressor described herein, is dictated by the following considerations. Since equal work is performed on the air passing through the compressor by each stage from the second to the ninth inclusive and since the said stages employ blades of identical aerofoil form and incidence, it will be understood that the whirl velocity of the air leaving the stator blades 9S is equal to Vw_3 . It is necessary that this whirl velocity should be removed from the air stream by the last row of stator blades 10S, before the said air enters the diffusers 12, and therefore the last row of stator blades must not only eliminate the whirl velocity applied by the rotor blades 10R but must also remove the residue of the whirl velocity originally imparted by the inlet guide vanes 11 and maintained throughout succeeding stages of the blading. In consequence there will be a considerable increase in pressure in the air passing through the stator blades 10S and, for reasons similar to those hereinbefore explained in connection with the first stage, it is desirable that the axial velocity Va should be increased, or at least not reduced, in passing through the said stator blades of the last stage: to this end it is obviously beneficial to reduce the axial velocity at which the air is introduced to the stator blades and this is achieved by increasing the width of the annular air passage in the neighbourhood of the leading edge of the said blades. It will be noted in Fig. 1 that there is a substantial reduction in the radius of the rotor drum across the last row of rotor blades, the radius of the stator remaining constant, and consequently the cross-sectional area of the passage increases across the row of blades of the last stage; thereby there is effected a departure from the uniform convergence of the annular passage between the rotor and the stator.

In addition, the rotor blades 10R may be so shaped that the whirl velocity which they impart to the air is less than the whirl velocity applied by other rows of rotor blades. The work done by the tenth stage may be, from this cause, materially less than the work done by pre-

vious stages, but it results in an increase in static pressure over the whole stage comparable to the increase in pressure over previous stages, the reduction in work being offset by the total diffusion of the residual whirl velocity. It is realized that the residual whirl velocity V_{w3} could be eliminated progressively from stage to stage down the compressor, but this would entail a change in the blade design from stage to stage with attendant manufacturing complications: it is preferable to accept the aforesaid high loading of the blades 10S and to ameliorate it by arranging that a substantial proportion of the diffusion occurs in the rotor blades 10R, thereby transferring some of the loading from the stator blades to the said rotor blades.

It will be understood that the form of the invention herein shown and described is to be taken as a typical example of the same, and that various changes in the relative size and arrangement of the parts may be resorted to without departing from the spirit of the invention or the scope of the subjoined claims.

What I claim as my invention is:

1. An axial flow compressor having a stator, a rotor journalled coaxially within the stator and defining therewith an annular passage, and blades extending across the said passage and mounted in circumferential rows alternately upon the stator and the rotor, each row of rotor blades with the row of stator blades next downstream constituting a stage of the compressor, adjacent rows of blades interacting aerodynamically so that on rotation of the rotor a stream of air is drawn through the passage and progressively compressed therein, the characteristics of the flow of air entering each successive stage after the first stage depending on the blade characteristics of the preceding stages, the cross-sectional area of the passage at the stages intermediate the first and last stages diminishing progressively in a downstream direction, the cross-sectional area of the passage at the first stage diminishing at a rate which is less than the rate of diminution of the cross-sectional area of the passage at the said intermediate stages, and the cross-sectional area of the passage at the last stage diminishing at a rate which is less than the rate of diminution of the cross-sectional area of the passage through the said intermediate stages in order to impress on the air which has been given flow characteristics in the preceding stages 45 desired flow characteristics on finally leaving the compressor.

2. An axial compressor as claimed in claim 1 in which the cross-sectional area of the passage diminishes more rapidly across the row of stator blades of the first stage 50 than across the stages intermediate the first and the last stages.

3. An axial flow compressor having a stator, a rotor journalled coaxially within the stator and defining therewith an annular passage, and blades extending across the said passage and mounted in circumferential rows alternately upon the stator and the rotor, each row of rotor blades with the row of stator blades next downstream constituting a stage of the compressor, adjacent rows of blades interacting aerodynamically so that on rotation of the rotor a stream of air is drawn through the passage and progressively compressed therein, the characteristics of the flow of air entering each successive stage after the first stage depending on the blade characteristics of the preceding stages, the cross-sectional area of the passage at the stages intermediate the first and last stages diminishing progressively in a downstream direction, the cross-sectional area of the passage at the first stage diminishing at a rate which is less than the rate of diminution of the cross-sectional area of the passage at said intermediate stages, the cross-sectional area of the passage at the last stage diminishing at a rate which is less than the rate of diminution of the cross-sectional area of the passage through the said intermediate stages in order to impress on the air which has been given flow characteristics in the preceding stages desired flow characteristics on finally leaving the compressor, the diameter of the stator at the first stage and at least two consecutive stages upstream of the last stage being uniform, while the diameter of the rotor progressively increases in a downstream direction at the first stage and at least one of the stages next preceding the last stage, and the diameter of the rotor at the other stages excepting the last stage being uniform while the diameter of the stator at the stages other than the previously mentioned stages of uniform diameter and other than the last stage decreases in a downstream direction.

4. An axial compressor as claimed in claim 3 further characterized in that the diameter of the rotor gradually decreases in a downstream direction across the last stage.
